CLAIM

The ornamental design for a cat scratching pad, as shown and described.

DESCRIPTION

FIG. 1 is a left side elevation view of a cat scratching pad showing our new design;

FIG. 2 is a right side elevation view thereof;

FIG. 3 is a front elevation view thereof;

FIG. 4 is a rear elevation view thereof;

FIG. 5 is a perspective view thereof;

FIG. 6 is a top plan view thereof; and,

FIG. 7 is a bottom plan view thereof.

1 Claim, 3 Drawing Sheets
